UNITED STATES PATENT OFFICE.

LUCIUS D. GOULD, OF NEWARK, NEW JERSEY.

STOVE-LID, &c.

SPECIFICATION forming part of Letters Patent No. 516,373, dated March 13, 1894.

Application filed September 25, 1893. Serial No. 486,492. (No model.)

To all whom it may concern:

Be it known that I, LUCIUS D. GOULD, a citizen of the United States, residing at Newark, in the county of Essex and State of New Jersey, have invented certain new and useful Improvements in Stove Lids or Covers; and I do hereby declare the following to be a full, clear, and exact description of the invention, such as will enable others skilled in the art to 10 to which it appertains to make and use the same, reference being had to the accompanying drawings, and to letters of reference marked thereon, which form a part of this specification.

The object of this invention is to prevent 15 the center lid or cover of a stove or range from sagging when subjected to high heat and the weight of the covers supported by said center, and to thus maintain a more level and even top surface on said range or stove and 20 closer joints between the parts.

The invention consists in the improved 25 cover or lid and in the arrangements and combinations of parts, all substantially as will be hereinafter set forth and finally embraced in the clauses of the claim.

Referring to the accompanying drawings in 30 which like letters indicate corresponding parts in each of the figures, Figure 1 is a plan of a center lid or cover, and Figs. 2 and 3, sections of the same on lines *x* and *y*, respectively, the 35 said lid being shown in each view in reverse position.

In said drawings, *a* indicates the center lid or cover having arms *a'*, *a'*, *a'*, which project 40 from the central part to engage the body of the stove and be supported thereby. The sides of said arms are curved as at *a*³, *a*³, *a*³, which curves supplement similar curves on adjacent parts of the stove or range and are 45 adapted to complete the formation of round pot-holes in the ordinary way. Said sides are provided with projecting ribs, *a*⁴, to strengthen the lid and provide suitable supports for the round lids which close said pot-holes. These 50 parts are of ordinary construction and may be modified at pleasure to suit varying conditions.

On the under side of the lid or cover, *a*, are 55 raised bridges *b*, *b'*, *b'*, cast integrally on the lid and lying longitudinally at the centers of the arms. Said bridges integrally join the

center part of said lid with the outer ends of the arms and are arched over the centers of the arms so as to form open spaces, *b*², at said centers. The inner upturned ends of the 55 bridges come together at the center of the lid on a plane very close to that of the lid, there being no intersecting of arches or integral connections of or between the same back from the extremities tending to act against uplifting pressure due to expansion. On the contrary the expansion arches are independent of one another excepting where they unite integrally with one another and with the body of the lid at the plane of said lid. 60

When the lids or covers are heated by the fire of the stove in ordinary service, and the same are subjected also to the weight of the pots, &c., upon said stove, the expansion of the metal of the bridges produces an upward 70 pressure at the center of the lid, which serves to resist the tendency to sag at that point. This upward pressure at the center is rendered positive because of the opposition pressures of the extremities of the expansion bridges 75 acting together on the lid. The central part of the said lid-center is thus held level, holding the round lids properly in place so that no open joints are formed and escape of heat therethrough allowed. 80

Where the center lid is provided with three arms *a'*, *a'*, *a'*, as shown in Fig. 1, I arrange the expansion bridges so that the bridges *b*', *b*', form the same obtuse angle on opposite sides of the bridge, *b*, and thus the pressure 85 of said bridges, *b*', bear equally against the end of the bridge, *b*, from opposite sides, thus preventing a warping of the lid.

I am aware that the construction shown may be modified without departing from the 90 invention.

Having thus described the invention, what I claim as new is—

1. The improved stove lid herein described having on the under side thereof cast bridges, 95 the inner upwardly turned ends of which integrally connect one with the other and with the body of the lid at the center of the said body, substantially as set forth.

2. The improved center lid for stoves having arms, *a*, *a*, *a*, and on the under side thereof integral therewith, having bridges, *b*, *b'*, *b'*,

disposed longitudinally with respect to said arms, the said bridges coming together at their upturned inner ends at the plane of the body and the bridges b', b' , being disposed at 5 uniform obtuse angles with the bridge, b , so that the expansion pressure will be directed uniformly against said bridge, b , from opposite sides substantially as set forth.

In testimony that I claim the foregoing I have hereunto set my hand this 17th day of to August, 1893.

LUCIUS D. GOULD.
